APPARATUS FOR THE PREPARATION AND EMBEDDING OF TISSUE SPECIMENS

John E. P. Pickett, 3323 Pinnafore Drive,
Durham, N.C. 27705

Filed June 15, 1970, Ser. No. 23,470

Term of patent 14 years

Int. Cl. D24—02

U.S. Cl. D16—2

FIG. 1

FIG. 4

FIG. 2

FIG. 3

FIG. 5

FIG. 1 is a perspective view showing the front and left side of an apparatus for the preparation and embedding of tissue specimens embodying my new design;

FIG. 2 is a perspective view similar to that of FIG. 1 and showing several compartments having been opened;

FIG. 3 is a right side elevation view of the FIG. 1 apparatus design;

FIG. 4 is a left side elevation view of the FIG. 1 apparatus design; and

FIG. 5 is a rear elevation view of the FIG. 1 apparatus design in a reduced size.

I claim:

The ornamental design for an apparatus for the preparation and embedding of tissue specimens, substantially
